UNITED STATES PATENT OFFICE

STANLEY WISBITH, OF WAMPUM, PENNSYLVANIA

BAG CLOSURE

Application filed August 22, 1927. Serial No. 214,747.

The present invention relates to an improved cement bag and it has more particular reference to a novel closure therefor.

As is well known, it is the present practice to tie one end of the bag, usually by wire. When filling the bags at the packing plant, this usually necessitates holding the open end of the bag and then bunching it and afterwards tying the wire around the bunched portion. Then on the other end of the bag there is a valve in which the spout of the filling machine is placed for filling the bag.

This method of filling cement bags utilizes unnecessary time and labor at the packing plant and is disadvantageous to the contractor who receives the filled bags, for it necessitates ripping of the bags frequently when the wire cannot be moved in an expeditious manner. The result is a noticeable wastage of bags such as could otherwise be re-used if properly handled.

As a matter of fact, many bags which are thus roughly handled are practically useless and are frequently torn into rags and used as aprons by workmen, and in many other ways.

Having observed these disadvantages and apparent defects, I have conceived of a new type of closure for a cement bag which overcomes the same.

Briefly, I propose to do away with the valve and to provide a novel type of closure on the open end of the bag which is of the slidable fastener type to thus facilitate filling, dumping, and handling.

In the drawings:—

Figure 1 is a fragmentary perspective view of the bag embodying the improved fastening means.

Figure 2 is a top plan view of the same showing the bag ready for storage or shipping.

Figure 3 is an end view of Figure 2 looking at the right hand end.

In the drawings; the reference character 4 designates the cement bag or sack which is of the customary construction. As before stated however, the valve (not shown) can be entirely eliminated if desired, for in this

arrangement, the bag can be filled through the open end. On the last named end we find a pair of complementary flexible metallic tracks which cooperate in forming a separable runway designated generally by the reference character 5. Slidably mounted on these is a wedge-shaped fastener 6 of somewhat conventional construction, the same being formed with a finger grip 7. As is obvious, when the bag is open, the fastener is on the left hand end of the runway and when it is desired to close it, it is simply gripped and shifted over to the right hand end as shown in Figure 1. In addition to these details, however, I provide a strap 8 which is fastened at one end to one side of the bag and which is adapted to be brought over the slidable fastener 6 and fastened down as indicated in Figures 2 and 3. In this connection I provide a patch 9, the same carrying a headed stud 10 cooperating with a snap fastener 11 on the free end portion of the strap. Thus, the strap is simply brought over the slidable fastener and then is snapped down by the fastener to prevent accidental opening thereof until the required time.

Obviously, a construction of this class is advantageous not only in facilitating filling and dumping, but it serves to permit the bag to be filled in a more uniform manner so that full measure is always had. It tends to cause the workmen to respect the bag to the extent that it is re-used many, many times. The invention facilitates storage, in that the bags can be packed in a more convenient manner. These and other advantages and features of the invention have obviously been made apparent from the description and drawings. Therefore, a more lengthy description is thought unnecessary.

I claim:—

As a new product of manufacture, a material container comprising, in combination, a bag provided at its open end with a closure including a sectional flexible runway embodying longitudinal interlocking track members and a clip fastener slidable along said track members, said clip being moved in one direction along the runway for opening the bag and being moved in the opposite

direction to one end of the runway for closing the bag, and means on the bag at the last named end of said runway for covering and cooperating with the fastener clip to prevent accidental opening of the latter, said means comprising a strap fastened at one end on one side of the bag, said strap being provided at its free end with a snap fastener, and a tab on the opposite side of the bag provided with a headed stud to which said snap fastener is cooperable, said strap being intended to extend transversely across the end of the bag and over top of the clip.

In testimony whereof I affix my signature.
